UNITED STATES PATENT OFFICE.

WILLIAM B. LUCAS, OF CHICAGO, ILLINOIS.

MOTOR-CONTROLLER.

973,525.

Specification of Letters Patent. Patented Oct. 25, 1910.

Application filed March 10, 1909. Serial No. 482,580.

To all whom it may concern:

Be it known that I, WILLIAM B. LUCAS, a citizen of the United States of America, and a resident of Chicago, Cook county, State of Illinois, have invented certain new and useful Improvements in Motor-Controllers, of which the following is a specification.

The main objects of this invention are to provide an improved form of electric controller particularly adapted for the purpose of automatically reducing the starting resistance in an electric motor circuit; to provide an improved mechanism capable of being controlled by the rotation of the motor controlled and adapted to positively insure the change of the resistance required for any variation of speed of the motor controlled; to provide an improved construction of the contact devices whereby injury to the motor controlled by the operation of said motor is practically impossible; to provide improved contact devices and mechanism for causing reduction of resistance in the circuit of the motor controlled; to provide an improved form of structure to hold the contact devices in position; to provide an improved device of this class in which the control is accomplished by the action of a liquid conductor under centrifugal force; and to provide improved means for containing the operating liquid.

A specific construction embodying this invention is illustrated in the accompanying drawings, in which:

Figure 1 is a longitudinal section, partly broken away, of an electric controller constructed according to this invention, the brushes and conductors being shown diagrammatically. Fig. 2 is a transverse section on the line A—A of Fig. 1, the position of the liquid when the shaft is at rest being indicated by full lines, and other portions of the surface of the liquid, depending on the speed of rotation, being indicated by dotted lines.

In the construction shown, the receptacle 1 has a cavity 2 supporting a liquid 3. A plurality of contact devices are mounted on the receptacle, and each comprises an inner part or terminal bar 4, disposed substan-

tially parallel with the axis of the receptacle, and substantially flush with the inner surface of the cylindrical wall of the receptacle, and an outer part or annular slip ring 5, each inner part 4 and its respective outer part 5 being connected by a conductor 6. In the form shown, the bars 4 are spaced apart circumferentially and the slip rings 5 are spaced apart axially. The shaft 7 is placed concentric with the receptacle. 60

In the form shown in the drawings the body of the receptacle is made of insulating material. The cavity 2 is made concentric with the receptacle. The bar contact devices 4 are mounted on the receptacle 1. 65 Each bar 4 is respectively connected with a slip ring 5 by a connector 6. Individual brushes 8 bear on the slip rings 5, and conductors 9 are connected to the brushes 8. In the form shown, each of the conductors 70 represents a resistance interposed between an adjacent pair of brushes.

The operation of the device shown is as follows:—When the receptacle is rotated, the liquid 3, due to friction and centrifugal 75 force, will successively engage the bars 4. During rotation the liquid 3 makes contact with a gradually increasing number of the bar contact devices 4, and finally makes a complete ring contact with all the contact 80 devices. Assume, for example, that the device is mounted directly upon the shaft of a motor, that the conductors 9 are resistances interposed between the contact devices, and that all are connected in circuit 85 with said motor. Then when the receptacle is rotated at a gradually increasing speed, the liquid will at first remain stationary in the bottom and will at this time serve to successively connect different resistances. 90 As the speed increases, the friction of the walls of the receptacle on the exposed surfaces of the liquid will tend to cause the liquid to follow the rotation of the receptacle. This, being resisted by the force of 95 gravity, will result in the liquid gradually extending so as to simultaneously cover a larger part of the inner circumference of the cavity, and the number of resistances which are simultaneously short-circuited 100

will increase until at a certain critical speed the liquid will have become spread out in a continuous ring, short-circuiting all the conductors and thereby cutting out all of 5 the resistance.

Although but one specific embodiment of the invention is herein shown and described, it will be understood that numerous details of the construction shown may be altered 10 or omitted without departing from the spirit and scope of this invention.

I claim:—

1. In a motor controlling device, a fixed starting resistance, a rotary element, terminals for said resistance carried by said element, and mechanism for automatically short-circuiting said terminals when the speed of the motor is accelerated. 15

2. In a motor controlling device, a fixed starting resistance, a rotary element driven by the motor, terminals for said resistance carried by said element, and mechanism for automatically short-circuiting said terminals when the speed of the motor is accelerated 20 and for opening said short circuit when the speed of the motor is diminished.

3. In a motor controlling device, a plurality of fixed resistances, a rotary element driven by the motor, terminals for said resistances carried by said element, and mechanism for automatically short-circuiting said terminals when the speed of the motor is accelerated, the number of terminals thus short-circuited depending upon the amount 35 of acceleration of the speed.

4. In a motor controlling device, a fixed starting resistance in circuit with the motor, a rotary element driven by the motor and carrying terminals for said resistance, and 40 mechanism for automatically short-circuiting the terminals of said resistance when the speed of the motor is accelerated.

5. In a motor controlling device, a fixed resistance in circuit with the motor, a rotary element driven by the motor and carrying terminals for said resistance, and mechanism for wholly or in part automatically short-circuiting the terminals of said resistance as the speed of the motor is accelerated 45 and, the amount of the resistance thus short-circuited depending upon the amount of acceleration of the speed.

6. In a motor controlling device, a receptacle rotatably mounted and having a cavity 55 therein for supporting a liquid, a liquid conductor in said cavity, a series of contact devices in the wall of said cavity, being spaced apart circumferentially and substantially flush with the inner surface of said wall, and 60 means outside of said receptacle connected electrically with said contact devices adapted to be automatically short-circuited by

the liquid when the speed of the motor is accelerated.

7. In a motor controlling device, a receptacle rotatably mounted and having a cavity therein for supporting a liquid, a liquid conductor in said cavity, a series of contact devices in the wall of said cavity, being spaced apart circumferentially and substantially 70 flush with the inner surface of said wall, a plurality of contact surfaces on the periphery of said receptacle respectively connected with said contact devices, and brushes located to engage said contact surfaces during 75 the rotation of said receptacle.

8. In a motor controlling device, a receptacle rotatably mounted and having therein a cavity substantially concentric with the axis of said receptacle, a liquid conductor in said cavity, the wall of said cavity comprising a series of circumferentially spaced contact segments insulated from each other and having their inner faces substantially 80 flush with the inner surface of the wall of 85 said cavity, contact surfaces on the periphery of said receptacle insulated from each other and electrically connected respectively with said contact segments.

9. In a motor controlling device, a receptacle rotatably mounted having a cavity 90 therein for supporting a liquid, a liquid conductor in said cavity, a series of contact devices in the wall of said cavity, each having an inner part substantially flush with the inner surface of said wall, and having an outer part electrically connected with the inner part, brushes located to engage said outer parts of said contact devices during the rotation of said receptacle, and controlling resistance connected between said brushes, said inner parts being spaced apart 100 circumferentially.

10. In a motor controlling device, a receptacle rotatably mounted having a cavity 105 therein for supporting a liquid, a flowing conductor in said cavity, a series of insulated contact devices in the wall of said cavity, each having an inner part substantially flush with the inner surface of said wall, said inner parts being spaced apart 110 circumferentially, brushes located to engage said contact devices during the rotation of said receptacle, and controlling resistance connected between said brushes. 115

11. In a motor controlling device, a fixed starting resistance in circuit with the motor, a rotary element driven by the motor and carrying terminals for said resistance, and mechanism adapted to maintain a short circuit between the terminals of the resistance at one speed of the motor and to maintain an interrupted condition of said short circuit for a lower speed of the motor. 120

12. In a motor controlling device, a plurality of fixed resistances, a rotary element driven by the motor, terminals for said resistances carried by said element, and mechanism for automatically maintaining a short circuit between a desired number of said terminals for one speed of the motor and adapted to maintain said short circuit be- tween a less number of said terminals for a lower speed of the motor. ¹⁰
Signed at Chicago this 8th day of March, 1909.
